United States Patent Office

Des. 227,630
Patented July 10, 1973

227,630

LAWN SWING

Romeo Oliva Gaucher, Bonneyville, Alberta, Canada

Filed July 11, 1972, Ser. No. 270,607

Term of patent 14 years

Int. Cl. D6—02

U.S. Cl. D6—52

—Fig. 2—

FIG. 1 is a perspective view of a lawn swing showing my new design; and FIG. 2 is an end view thereof.

I claim:

The ornamental design for a lawn swing, as shown.
